UNITED STATES PATENT OFFICE

2,433,792

RENEWABLE CARTRIDGE FUSE

Omer W. Smith, Owensboro, Ky.

Application November 30, 1943, Serial No. 512,305

4 Claims. (Cl. 200—131)

1

This invention relates to renewable cartridge fuses.

An object of the present invention is to provide a cartridge fuse wherein the fuse link may be easily and quickly replaced.

Another object of the present invention is to provide a cartridge fuse in which the case is made of a transparent material, thereby enabling upon a glance the determination of the condition of the contained fuse link.

A further object of the present invention is to provide a cartridge fuse which includes fewer parts and is cheaper to manufacture than the fuses as heretofore produced.

Other objects and advantages will be apparent from the following description of the illustrative embodiments of fuses according to the present invention as shown in the accompanying drawings, wherein:

Figure 1 is a side elevational view of a cartridge fuse according to the present invention.

Figure 2 is a plan view of the cartridge fuse shown in Figure 1.

Figure 3 is a side elevational view, in section, taken on the line 3—3 of Figure 2.

Figure 4 is a side elevational view of a modification of the cartridge fuse shown in Figure 1.

Figure 5 is a plan view of the cartridge fuse shown in Figure 4.

Figure 6 is a sectional view taken on the line 6—6 of Figure 5.

Figure 7 is a partial side elevational view, in section, of the upper portion of the cartridge fuse shown in Figure 4.

Referring to Figures 1 to 3 inclusive of the drawings, the numeral 1 indicates the case which is molded of a suitable plastic or glass either clear or colored. Although the case is shown as being rectangular in shape, it may be of cylindrical form. Moulded into the ends of the case 1 and passing through apertures in said ends are the copper terminals 2. The terminals are positioned with respect to the case by molding the case around the terminals so that an integral unit will be formed. Each of the terminals 2 is provided with a shelf member 6 having a threaded aperture 7 adapted to receive a post or headed screw 5 therein. The screws 5 in each of the shelf members of the terminals 2 are for the purpose of detachably securing the ends of a fuse link 8 to the terminals 2, said link extending between the shelf members in a horizontal plane parallel to the base of the case 1. The case 1 is provided with a cover 4 which may be of a material similar to that employed in fab-

2

ricating the case and which is detachably secured to the top of the terminals 2 by means of screws 3 passing through countersunk apertures in the cover, with the threaded end of each of said screws being in threaded engagement with a complementary threaded opening in the top of each of the terminals 2.

In the modification of the cartridge fuse according to the present invention as shown in Figures 4 to 7 inclusive, the copper terminals 12 extend into the plain or colored transparent case 11. As was the case with the form of the invention shown in Figures 1 through 3, the case is composed of plastic or glass, either clear or colored, and is molded about the terminals 12 so as to form a single unit of rigid construction. Each of the terminals 12 is provided with a shelf member 16, Figure 6, having a threaded opening 17 in the top thereof. In the shelf member 16 of each of the terminals, there is a groove 18 extending transversely therethrough, said groove being contiguous to an inclined wall 19 on the free end of the terminal.

Extending from one of the shelf members 16 to the other shelf member 16 of the terminals 12 is a fuse link 20, each end of the said link being mounted so that its bottom edge is supported in the groove 18 and its under face bears against the inclined wall 19 as clearly shown in Figure 6. The thus mounted end is detachably secured to the terminal 12 by means of a wedge block 21 and a post or headed screw 15, said screw passing through opening 22 in the wedge block 21 and having its end thereof in threaded engagement with the threaded opening 17 in the shelf member 16.

The case 11, Figure 7, is provided with a cover 14 of a material similar to that composing the case 11, which is detachably secured to the top of the terminals 12 by means of spring clips 23 and 24 carried by rivets 13 mounted in the cover 14, the spring clip 23 engaging a slot 25 in one of the terminals and the spring clip 24 having its free end in engagement with the under side of a metal strip 26 carried by the opposing terminal.

Having fully described the invention, what I claim as new and desire to secure by Letters Patent is:

1. A renewable cartridge fuse, comprising: an elongated hollow body portion of moulded insulating material having end portions and a wall portion providing an open side; a pair of end terminals of conducting material, one of said terminals extending into said hollow body through each end portion thereof, said body

having its end portions moulded about said terminals and having a portion of insulating material extending over each of said terminals and cooperating with said wall portion to form a boundary for said open side, said terminals having seat portions for receiving the ends of a fuse link extending between said terminals; means for detachably securing the ends of said fuse link to said seat portions; a cover member of transparent insulating material having edge portions fitting the boundary of said open side to close said hollow body; and means for detachably securing said cover member in position on said body member.

2. A renewable cartridge fuse, comprising: an 15 elongated hollow body portion of moulded insulating material having end portions and a wall portion providing an open side; a pair of end terminals of conducting material, one of said terminals extending into said hollow body through each end portion thereof, said body having its 20 end portions moulded about said terminals and having a portion of insulating material extending over each of said terminals and cooperating with said wall portion to form a boundary for said open side, said terminals having seat portions for receiving the ends of a fuse link extending between said terminals; means for detachably securing the ends of said fuse link to said seat portions; a cover member of transparent insulating material having edge portions fitting the boundary of said open side to close said hollow body; and threaded means received by said terminals for detachably securing said cover member in position on said body member.

3. A renewable cartridge fuse comprising: a pair of terminal members having a seat portion; a case of insulating material molded around said terminal members so as to form an integral structure and inclose said seat portion, each seat 40 portion having a wall extending at an angle thereto and arranged transversely thereof; a fuse link arranged in said case so that the opposite ends thereof engage said inclined walls; means for detachably securing said fuse link to each of said terminal members including a block having an inclined surface engaging said fuse link and means for securing the same to the seat

5 portion of its associated terminal member; and means for detachably securing a transparent cover plate over said fuse link including spring clips in association with complemental means of said terminals.

10 6. A renewable cartridge fuse, comprising: a pair of terminal members each having a seat portion; a case of insulating material molded around said terminal members to form an integral structure and inclose said seat portions, each of said seat portions having a groove extending transversely thereof, each of said terminal members also having a wall extending upwardly and outwardly from its transverse groove; a fuse link arranged in said case so that the opposite ends thereof engage said inclined walls and also rest in said grooves; and means for detachably securing said fuse link to each of said terminal members including a block having an inclined surface engaging said fuse link and a fastening member extending through said block and securing the same to the seat portion of its associated terminal member.
